Patented May 4, 1926.

UNITED STATES PATENT OFFICE.

PATRICK F. LYNN, OF PITTSTON, PENNSYLVANIA.

FORCE-DRAFT APPARATUS.

Application filed December 28, 1925. Serial No. 78,018.

To all whom it may concern:

Be it known that I, PATRICK F. LYNN, a citizen of the United States, and a resident of Pittston, in the county of Luzerne and

5 State of Pennsylvania, have invented a new and Improved Force-Draft Apparatus, of which the following is a full, clear, and exact description.

This invention relates to force draft apparatus and more particularly to such apparatus as applied to locomotives, and is designed more particularly for use in a locomotive burning hard coal.

Various attempts have been made to fire straight anthracite coal in a locomotive but all attempts, so far as I am aware, have proven failures with locomotives such as constructed, and it is the object of my invention to provide a force draft mechanism 20 which will supply the necessary air draft at the proper points to insure a full and complete combustion whether the engine be running or at a standstill.

With these and other objects in view, the invention consists in certain novel features of construction and combinations and arrangements of parts, which will be more fully hereinafter described and pointed out in the claims.

30 In the accompanying drawings—

Figure 1 is a view in longitudinal section through a portion of a locomotive, showing my improvements attached thereto;

Figure 2 is a view in horizontal section 35 on the staggered line 2—2 of Figure 1;

Figure 3 is a view on a reduced scale on the line 3—3 of Figure 1.

1 represents the boiler and 2 the fire box of a locomotive 3. This fire box I provide 40 with an air-tight ash pit 4 below the grate 5, any suitable means of course being provided to permit the ashes to be dumped although I have not attempted to illustrate any structure for this purpose.

45 Inside of the ash pit 4 and below the grate 5 I provide a series of air pipes 6 which preferably taper longitudinally or closed at their rear ends, and at their forward larger ends project through the wall of the ash pit 50 4 and are secured to or form an integral part of a manifold 7.

These pipes 6 have upwardly projecting air discharge nozzles 8 in any desired number and extending throughout the pipes 55 within the ash pit so as to discharge air upwardly through the grate and the coal. To

prevent ash from falling into these nozzles 8 during the poking of the fire or shaking of the grate, I provide covering strips 9 which are fixed to a board 10 at one end and 60 constitute a frame slidably mounted on bars 11 and movable by a rod 12 and arm 13 projected into the cab 14 of the locomotive so that the fireman can position these strips 9 above or at one side of nozzles 8 as he may 65 desire.

The air manifold 7 has an inlet pipe 15 which communicates with a blower 16, and this blower is attached to the locomotive in any suitable manner and is operated by a 70 shaft 17 supported in suitable bearing brackets 18 and 19 depending from the locomotive boiler 1. A bevel pinion 20 on shaft 17 is adapted to mesh with a bevel pinion 21 on a shaft 22 located at right angles to shaft 17 and supported in a depending hanger or bracket 23 secured to the boiler 1.

A sprocket wheel 24 is fixed to shaft 22 and is connected by a sprocket chain 25 with a sprocket wheel 26 on one of the locomotive 75 axles 27 so that when these pinions 20 and 21 are in mesh and the locomotive is in motion the blower will be operated through the medium of the mechanism above described to force air through the nozzles 8.

28 represents a steam turbine which is secured in any approved manner to the bottom of boiler 1, and the drive shaft 29 of said turbine has a gear wheel 30 thereon meshing with a gear wheel 31 on a clutch member 32, this clutch member being loose on shaft 17. A clutch member 33 adapted to engage clutch member 32 is keyed to slide on shaft 17, and the hub 34 of pinion 20 above referred to is also keyed to slide on shaft 17, and said hub 34 is connected by an arm 35 with a longitudinally movable rod 36, said rod 36 being also connected by an arm 37 with clutch member 33.

The arms 35 and 37 and the rod 36 constitute a frame which is manually movable through the medium of any operating mechanism, not shown. The steam turbine 28 is connected by a pipe 38 with the boiler and is provided in the cab 14 with a manually 100 operated valve 39 to control the passage of steam to the turbine.

When the engine is at rest and it is desired to maintain a forced draft of air, the rod 36 is moved to the left of Figure 2 to 110 move the pinion 20 out of mesh with pinion 21 and to move the clutch member 33 into

locked engagement with clutch member 32. Valve 39 is then opened and the steam will cause the turbine 28 to operate, and through the medium of the shaft 29 and gear wheels 30 and 31 motion will be transmitted to the shaft 17 to operate the blower 16.

In the pipe 15 at the outlet of the blower 16 I provide a throttle valve 40 which may be manually operated to control the volume of air discharged from the blower. It will thus be noted that when the locomotive is running, the rotary movement of one of the axles will operate the blower and air may be discharged through the several nozzles 8 and through the coal. When the locomotive is at rest, the turbine 28 will function to operate the blower and these parts and mechanisms are always under manual control so that just the desired amount of air drafts may be had at all times to insure an efficient burning of the coal.

Various slight changes and alterations might be made in the general form of the parts described without departing from my invention and hence I do not limit myself to the precise details set forth but consider myself at liberty to make such slight changes and alterations as fairly fall within the spirit and scope of the appended claims.

30 I claim:

1. The combination with a locomotive, of a blower located outside of the fire box, an outlet manifold communicating with the blower, a series of parallel air discharge pipes connected to the manifold and projecting into the ash pit below the grate of the boiler, said pipes tapering and of decreasing diameter from their air inlet to their closed inner ends, upwardly projecting air nozzles on said pipes, and a manually movable frame having strips thereon adapted to be positioned either above the nozzles or at one side thereof. 35

2. The combination with a locomotive, of a blower located outside of the fire box, an outlet manifold communicating with the blower, a series of parallel air discharge pipes connected to the manifold and projecting into the ash pit below the grate of the boiler, said pipes tapering and of decreasing diameter from their air inlet to their closed inner ends, upwardly projecting air nozzles on said pipes, a manually movable frame having strips thereon adapted to be positioned either above the nozzles 40 or at one side thereof, and means in the cab of the locomotive for manually controlling the operation of the frame and the power transmitting motion to the blower. 50

PATRICK F. LYNN.
